HEATING FURNACE

Julius H. Strassburger, Steubenville, Ohio, assignor to National Steel Corporation, a corporation of Delaware

Application August 25, 1943, Serial No. 499,946

17 Claims. (Cl. 263—2)

The present invention relates to heating furnaces for heating billets, blooms, slabs, bars and the like, and more particularly to the apparatus at the discharge end of the furnace for discharging therefrom the bars, billets, blooms, slabs or the like, which have been heated in the furnace.

In heating furnaces for heating bars, billets, blooms, slabs or the like it has been customary to pass the material continuously or intermittently through the heating chamber or through communicating heating and soaking chambers and then to discharge the material from the furnace at the discharge end by causing them to slide or roll downwardly by gravity along either an inclined portion of the furnace hearth or along water-cooled pipes spaced apart to form parallel skids. The material is generally deposited on the rolls of a roll table at the lower end of the skids and is carried away from the discharge end of the furnace by the table. In general, the roll table extends at right angles to the furnace but it may extend in the same general direction as the furnace so that the material may be carried forwardly instead of sidewise away from the discharge end of the furnace.

Considerable difficulty has been encountered where the conventional water-cooled pipes have been used as skids. When handling large blooms or billets, the skids are subjected to severe bumping and vibration and the conventional water-cooled pipes will not withstand the severe service to which they are subjected. It has been necessary heretofore to replace the water-cooled pipes periodically. This, naturally, requires a shutting down of the furnace and a consequent loss of production. Moreover, when these water-cooled pipes become bent or otherwise damaged by the severe treatment to which they are subjected, the blooms, billets, bars, slabs, etc. do not move uniformly downwardly along the skids and, hence, the material is subjected to severe treatment and is not deposited on the roll table in the desired position.

I have also found that where ordinary water-cooled pipes are used for skids the water cooling is not satisfactorily carried to the knuckle or joint between the furnace hearth and the skids and that, consequently, they afford no substantial protection to the refractory hearth at this point. As a consequence an excessive amount of wear takes place at this point and it is necessary to periodically shut down the furnace. This, of course, means a loss in production.

The present invention overcomes the objectionable features of the conventional skids. It

provides a skid structure which will carry the water cooling to the furnace hearth knuckle and which will withstand the rigid service to which the skids are subjected. Moreover, by virtue of the fact that the skids which I provide will withstand the rigid conditions to which they are subjected, they will effectually deposit the material in proper position on the roll table. The structure which I provide possesses the further advantage that it is inexpensive and relatively simple from the manufacturing standpoint.

In the accompanying drawings I have shown, for purposes of illustration only, one embodiment of my invention. In the drawings I have shown my invention as applied to a furnace for heating blooms, bars, slabs, etc., but it will be understood that my invention is not limited to furnaces for heating such articles but may be applied generally to the discharge end of any heating furnace in which the material being heated is passed continuously or intermittently therethrough.

In the drawings:

Figure 1 is a longitudinal sectional view through one of the skids and the supporting means therefor and a portion of the furnace adjacent the discharge end;

Figure 2 is a front elevational view showing certain parts of the structure shown in Figure 1, the rolls of the roll table being shown in section and only a portion of the brickwork between the skids being shown;

Figure 3 is a horizontal section taken above the skids and a part of the roll table, the brickwork between the skids and several of the other parts being eliminated for purposes of clarity;

Figure 4 is a top plan view of one of the skids shown in Figure 3;

Figure 5 is a side elevational view of the skid shown in Figure 4; and

Figure 6 is a transverse sectional view taken along the line VI—VI of Figure 5.

In the embodiment shown in the drawings the furnace 2 is provided with the usual top, bottom, side and end walls. The hearth or bottom wall 3, which is formed of a layer of chrome brick 4, a layer of fire brick 5 and a layer of insulation 6, is supported on the structural steel work indicated generally by the reference character 7. The hearth proper terminates within the furnace at a point spaced from the end wall 8 which has the discharge opening 9 therein. The skids, indicated generally by the reference character 10, at the upper ends thereof, are positioned in abutting relation with respect to the hearth and they bridge the area between the

end of the hearth and the discharge opening 9 and extend slightly beyond the discharge wall so that material passing thereover may be discharged onto a roll table indicated generally by the reference character 11. The discharge opening above the skids is normally closed by a door 12 which is pivotally mounted on the rod 13 carried by the angles 14. The angles 14 are supported by the channel 15 which extends across the discharge wall and acts as a reinforcement therefor. As is customary, the furnace door 12 is formed of a metal casting and the inner face thereof is lined with a refractory 16. This furnace door is normally in the closed position indicated in Figure 1, but whenever a billet, bar, slab or the like is being discharged from the furnace along the skids, the door is moved to open position. The movement of the door from closed to open position is effected by means of an operating rod 17, the lower end of which is pivotally connected at 18 to the metal frame of the door.

When a billet or the like is being discharged from the furnace, the door is raised and it passes downwardly along the skids 10 by gravity and is deposited on the roll table 11. The roll table 11 is made up of a plurality of rolls 19 which are supported in suitable bearings 20 carried by a supporting frame 21.

As stated above, a plurality of spaced, water-cooled skids bridge the space from the end of the furnace hearth to the roll table. Any suitable number of skids may be provided, depending upon the character of the material to be handled by the furnace and the length thereof. These skids are built-up structural members and are of such character that they can withstand the severe treatment to which they are subjected in use. Each skid comprises a bottom plate 27, side plates or bars 28 and a top plate or bar 29. The side plates 28 are supported on the bottom plate 27 and are positioned inwardly of the edges of the bottom plate. A wide bottom plate is preferably employed in order to provide support for the brickwork between the skids and in order to give rigidity and strength to the skids. The lower end of each skid is closed by a closure plate 30 and an apron plate 31. The apron plate 31 is welded or otherwise suitably secured to the bottom side of the top plate just short of the end thereof, and the closure plate 30, at one end, is welded or otherwise suitably secured to the rear face of the apron plate 31 and at the other end to the lower end of the bottom plate 27. As is indicated in Figures 1 and 5, the one edge of the plate 30 is bevelled to cooperate with the upper face of the bottom plate 27 at the end thereof.

The upper end of each skid is closed by means of a transversely extending closure plate 32. This closure plate is preferably welded to the ends of the top and side walls of the skid and to the top surface of the bottom plate at the upper end thereof.

The arrangement just described provides a completely enclosed chamber 33 through which water or some other cooling fluid may be circulated. The bottom plate of the skid has an opening 34 therein through which a water pipe 35 extends. The pipe 35 is bent intermediate its ends so that it extends downwardly through the chamber 33 to a point adjacent the bottom end thereof where the water is discharged from the pipe into the chamber 33. Water is fed to the pipe 35 by a pipe 36, one end of which is connected to the inlet header 37 which extends

transversely of the furnace adjacent the discharge end and supplies water to all of the pipes which feed water into the skids. The flow of water is regulated by a valve 38 in the pipe 36.

5 The bottom plate of each skid is provided with another opening 39 through which a discharge pipe 40 extends. This discharge pipe 40 is positioned adjacent the upper end of the skid and extends upwardly into the chamber 33 to a sufficient height to insure that the cooling fluid will reach the upper end of the skid. The discharge pipe 40 extends downwardly from the skid and at the bottom end thereof is connected to a transversely extending pipe 41. Separate discharge pipes 41 are provided for each of the skids and they extend transversely beneath the furnace and are connected with a water box 42 which, in turn, is connected with a pipe 43 which is adapted to empty into a sewer.

20 Supporting bars or plates 44 are provided near the lower end of each skid. These bars or plates form abutments against which the lower ends of the supporting plates 26 and the brickwork 80 between the skids rest. Each supporting bar 44 is welded to and mounted upon the bottom plate 27 and is welded to the adjacent side bar and the adjacent end of the top bar.

25 The upper end of each skid is provided with plates or bars 45 which extend beyond the upper end of the skid and into the brickwork forming the hearth of the furnace. One end of each bar is welded or otherwise suitably secured to an end of the crossbar 32 and the adjacent side bar 28. The other end of each bar extends beyond the 30 upper end of the skid and extends into the furnace hearth to a sufficient extent to reinforce the hearth and retard its deterioration. These bars or plates 45 are supported intermediate their ends by bars 46 which are welded thereto and 40 to the depending member 47 which is described below.

35 The upper end of each skid is also provided with a depending member 47 which assists in tying the skids into the furnace structure proper. 45 The depending member 47 is preferably formed from a billet. The upper end of this member is welded to the face of the crossbar 32 and the upper end of the bottom plate 27. It is positioned between the bars 45 and extends downwardly along the front face of the hearth of the furnace. This billet serves to strengthen the forward end of the furnace hearth and to prevent disintegration thereof due to the forward motion of the material being passed through the furnace which, as is evident, is pushed along the hearth by suitable pushing mechanism adjacent the charging end. The lower end of each billet 47 is provided with a hole 48 adapted to receive a pin or bar 49 which extends transversely of the furnace hearth and beneath it, and assists in holding the skid and other parts in position.

40 The skids are supported in position at the forward end of the furnace by the structure described below. The upper end of each skid rests upon a hearth slab 50 which, in turn, is supported by a channel 51 forming a part of the structural steel supporting framework for the furnace. A welded supporting stand 52 is provided for each skid. This supporting stand is formed of a top billet 53 and legs 54 which extend downwardly therefrom. These legs are likewise preferably made of billets and at their upper ends are welded to the lower face of the inclined top billet 53. The upper leg of the stand is supported on a plate 55 which is supported on the structural

steel work for the furnace. One face of the upper leg 54 and the upper end of the top supporting member 53 abut the slab 50. These parts may be welded together if desired, although ordinarily such welding is not desirable. A triangular plate 56 is welded to the top face of the plate 55 and the forward face of the upper leg 54 in order to impart rigidity to the structure. The lower leg 54 of each stand rests upon a transversely extending bearing plate 57 which, in turn, is supported by a concrete pedestal 59. The top member of the stand, the upper leg thereof and the bearing plate have holes therein to receive the water pipes mentioned above.

Each skid is provided with a downwardly extending slab 60 which is welded to the bottom plate near the lower end thereof. Each slab cooperates with a transversely extending supporting structure 61 which is adapted to support the lower end of the skid. This supporting member 61 rests upon the upper side of a box-like structure 62 which is formed of top and bottom channels 63 and side plates 64. This supporting box-like structure is held together and held in position by a rod 65 which extends through the plates and is threaded at one end to receive a nut 66. The rod extends through the pedestal 59 and is threaded at the other end to receive a nut 67. A bearing plate 68 is provided at this end of the rod in order to protect the pedestal which, as is indicated, is preferably made of concrete. When the nuts are threaded on the rods, the box-like structure is held together in the position indicated. A sleeve 69 surrounds the rod 65 throughout that portion which extends through the concrete supporting pedestal 59. A rod 70 extends upwardly through the box-like supporting structure and also through the lower portion of the support 61. The upper end thereof is threaded and receives a nut 71. In this way the supporting structure 61 is held in position on the box-like structure 62. Tie rods 72 extend through openings in the channel 73, which is a part of the structural steel work of the furnace, and the rear face of the supporting structure 61. The ends of these tie rods are threaded to receive nuts 74, and when these nuts are threaded in place the supporting member 61 and skids are held in proper position in respect of the furnace. There is a tendency for the skids to be pushed forwardly by the movement of the material onto the skids at the point where the skids join the hearth but the skids are restrained against any such forward movement by the supporting structure just described.

It will be apparent from this description that in the event that any of the skids are damaged for one reason or another they can be readily removed without any substantial shutdown of the furnace.

In the absence of brickwork between the skids, the furnace atmosphere would escape between them and outwardly from the discharge end of the furnace. However, the space between the skids is closed by brickwork 80 which rests upon plates 26 in the manner indicated in Figure 2.

Unless provision is made to prevent it, the top surfaces of the skids will wear to a substantial extent in normal operation. Consequently, I provide wearing strips 81 on the top surfaces thereof. These are preferably made of Meehanite, which is a heat-resistant and wear-resistant alloy. These strips extend from the upper end of each skid to the lower end and the material rests

thereon. Whenever the Meehanite strips become worn, they can be readily replaced.

It will be apparent from the above description that the structure which I provide possesses great strength and will withstand the severe conditions to which it is subjected in normal usage. The skids are built-up structural members and possess sufficient strength that they will not be bent or warped by the heat and the rough treatment which they receive. Also, it will be apparent that the skids are joined into the forward end of the hearth in such a way that the hearth is protected against wear resulting from the forward movement of the material thereover. It will also be apparent that the cooling fluid is fed to the skids adjacent the lower end thereof and then flows upwardly therethrough and is discharged therefrom at or adjacent the knuckle of the furnace hearth. This provides a constantly flowing body of water extending from the extreme lower end of the skids to the extreme upper end thereof, and the knuckle of the furnace as well as the skids will be kept relatively cool. Also, any steam which forms cannot be entrapped in the skids but will pass through the discharge pipe so that there will not be any possibility of hot spots developing at various points along the skids and particularly at the junction between the skids and the furnace hearth.

While I have shown and described a preferred embodiment of my invention, it will be understood that it can be otherwise embodied within the scope of the appended claims.

I claim:

1. A discharge skid for a heating furnace having a hearth over which the material passes comprising bottom, top, side and end plates united together to form a chamber for a cooling fluid, means for supplying a cooling fluid to said chamber adjacent one end thereof, means for discharging cooling fluid from the other end thereof adjacent the junction between the skid and the furnace hearth.

2. A discharge skid for a heating furnace having a hearth over which the material passes comprising bottom, top, side and end plates united together to form a chamber for a cooling fluid, means for supplying a cooling fluid to said chamber adjacent the lower end thereof, means for discharging cooling fluid from said chamber at the upper end thereof, and means carried by the upper end of the skid for connecting it with the furnace hearth.

3. A discharge skid for a heating furnace having a hearth over which the material passes comprising bottom, top, side and end plates united together to form a chamber for a cooling fluid, means for supplying a cooling fluid to said chamber adjacent the lower end thereof, means for discharging cooling fluid from the chamber at the upper end thereof adjacent the junction between the skid and the furnace hearth, and means carried by the upper end of the skid for reinforcing the end of the furnace hearth with which it is connected.

4. A discharge skid for heating furnaces comprising bottom, top, side and end plates united together to form a chamber for a cooling fluid, means for circulating a cooling fluid through said chamber, and at least one longitudinally extending hearth reinforcing plate carried by one end of said skid.

5. A discharge skid for a heating furnace having a hearth over which the material passes

comprising bottom, top, side and end plates united together to form a chamber for a cooling fluid, means for circulating a cooling fluid through said chamber, and a vertically extending member depending from the upper end of the skid and adapted to abut the end of the furnace hearth.

6. A discharge skid for a heating furnace having a hearth over which the material passes comprising bottom, top, side and end plates united together to form a chamber for a cooling fluid, said bottom plate extending sidewise beyond the side plates to provide supporting surfaces, means for circulating a cooling fluid through said chamber, at least one longitudinally extending hearth reinforcing plate carried by the upper end of the skid, and a vertically extending member depending from the upper end of the skid and adapted to abut the end of the furnace hearth.

7. Apparatus for discharging billets, blooms, bars and the like from a heating furnace having a discharge opening and a hearth over which the material passes comprising a plurality of spaced, substantially parallel skids extending downwardly at an angle from the hearth to the discharge opening, each skid having bottom, top, side and end plates united together to form a chamber for a cooling fluid, means for supplying a cooling fluid to each of said chambers adjacent the lower end thereof, and means for discharging cooling fluid from the upper end of each of said skids adjacent the junctions between the skids and the furnace hearth.

8. Apparatus for discharging billets, blooms, bars and the like from a heating furnace having a discharge opening and a hearth over which the material passes comprising a plurality of spaced, substantially parallel skids extending downwardly at an angle from said hearth to the discharge opening, each skid having bottom, top, side and end plates united together to form a chamber for a cooling fluid, means carried by the upper end of each skid for cooperation with the furnace hearth to reinforce it, means for supplying a cooling fluid to each of said skids adjacent the lower end thereof, and means for discharging cooling fluid from the upper end of each skid adjacent the junctions between the skids and the furnace hearth, the discharge means being arranged to provide flow of the cooling fluid in the skids to the end thereof adjacent the furnace hearth.

9. Apparatus for discharging billets, blooms, bars and the like from a heating furnace having a discharge opening and a hearth over which the material passes comprising a plurality of spaced substantially parallel skids extending from the end of the hearth to the furnace discharge opening, each skid having bottom, top, side and end plates united together to form a chamber for a cooling fluid and the bottom plate of each skid extending sidewise beyond the side plates to provide supporting surfaces, means for circulating a cooling fluid through each of said skids, and closure means extending between adjacent skids and supported by the bottom plates thereof.

10. Apparatus for discharging billets, blooms, bars and the like from a heating furnace having a discharge opening and a hearth spaced therefrom over which the material passes comprising a plurality of spaced skids extending at an angle downwardly between the end of the furnace hearth and the furnace discharge opening, each skid having bottom, top, side and end plates united together to form a chamber for a cooling fluid, means for circulating a cooling fluid

through each of said skids, means for supporting said skids, and means for maintaining the upper end of each skid in abutting relation with the end of said furnace hearth.

11. Apparatus for discharging billets, blooms, bars and the like from a heating furnace having a discharge opening and a hearth spaced therefrom over which the material passes comprising a plurality of spaced skids extending at an angle downwardly from the end of said hearth to the discharge opening, each skid having bottom, top, side and end plates united together to form a chamber for a cooling fluid, means for circulating a cooling fluid through each of said skids, at least one hearth reinforcing plate carried by the upper end of each skid and extending into the furnace hearth, a stand having an inclined upper surface adapted to support each skid intermediate the ends thereof, and means for maintaining the upper end of each skid in abutting relation with the furnace hearth with the reinforcing plates extending into the hearth.

12. Apparatus for discharging billets, blooms, bars and the like from a heating furnace having a discharge opening and a hearth spaced therefrom over which the material passes comprising a plurality of spaced skids extending downwardly at an angle from the furnace hearth to the furnace discharge opening, each skid comprising bottom, top, side and end walls united together to form a chamber for a cooling fluid, means for supplying a cooling fluid to each chamber adjacent the lower end thereof, means for discharging the cooling fluid from each chamber adjacent the upper end thereof, a vertically extending member depending from the upper end of each skid and adapted to abut the end of the furnace hearth, said depending members extending downwardly to a point below the bottom of the hearth, means cooperating with each of said depending members for holding them against vertical movement when in position against the end of the hearth, means for supporting each of said skids intermediate the ends thereof, and means for maintaining the skids and the depending members thereon in abutting relation with the end of said hearth.

13. Apparatus for discharging billets, blooms, bars and the like from a heating furnace having a discharge opening and a hearth spaced therefrom over which the material passes comprising a plurality of spaced skids extending at an angle downwardly from the end of said hearth to the discharge opening, each skid having bottom, top, side and end plates united together to form a chamber for a cooling fluid, means for circulating a cooling fluid through each of said skids, at least one hearth reinforcing plate carried by the upper end of each skid and extending into the furnace hearth, a stand having an inclined upper surface adapted to support each skid intermediate the ends thereof, and means for maintaining the upper end of each skid in abutting relation with the furnace hearth with the reinforcing members extending into the hearth, and closure means extending between and supported by said skids.

14. Apparatus for discharging billets, blooms, bars and the like from a heating furnace having a discharge opening and a hearth spaced therefrom over which the material passes comprising a plurality of skids extending downwardly at an angle from the hearth to the discharge opening, each skid having bottom, top, side and end plates united together to form a chamber

for a cooling fluid, means for circulating a cooling fluid through each of said chambers, means for supporting the upper end of each of said skids, means for supporting the skids intermediate the ends thereof, a depending member carried by each of said skids, and means for maintaining the upper end of each skid in abutting relation with the end of the furnace hearth.

15. Apparatus for discharging billets, blooms, bars and the like from a heating furnace having a discharge opening and a hearth spaced therefrom over which the material passes comprising a plurality of spaced skids extending downwardly at an angle from the furnace hearth to the furnace discharge opening, each skid having bottom, top, side and end walls united together to form a chamber for a cooling fluid, means for supplying a cooling fluid to the lower end of each of said chambers, means for discharging cooling fluid from each of said chambers adjacent the upper end thereof, said discharge means being arranged to cause cooling fluid to contact the upper end of each of said skids, at least one plate carried by the upper end of each of said skids and adapted to extend into the hearth, means for supporting said skids, and means for maintaining the upper end of each skid in abutting relation with the end of the hearth and said plates within the hearth.

16. Apparatus for discharging billets, blooms, bars and the like from a heating furnace having

a discharge opening and a hearth spaced therefrom over which the material passes comprising a plurality of spaced, substantially parallel skids extending downwardly at an angle from the hearth to the discharge opening, each skid having bottom, top, side and end walls united together to form a chamber for a cooling fluid, means for circulating a cooling fluid through each of said skids from the lower end to the upper end thereof, means for supporting the upper end of each of said skids adjacent the end of said hearth, means for supporting the skids intermediate the ends thereof, and means cooperating with each of said skids for maintaining the upper ends thereof tightly against the end of said furnace hearth.

10 15 20 25 30 35

17. Apparatus for discharging billets, blooms, bars and the like from a heating furnace having a hearth over which the material passes comprising a plurality of spaced, substantially parallel skids, each skid having bottom, top, side and end plates united together to form a chamber for a cooling fluid, means for supplying a cooling fluid to each of said skids adjacent one end thereof, means for discharging cooling fluid from each of said chambers at the end thereof adjacent the furnace hearth, and means for supporting each of said skids and for maintaining the discharge end thereof in abutting relation with the end of said furnace hearth.

JULIUS H. STRASSBURGER.
